SHUTTLE BOX PLATE

Everett H. Ashton, Jersey City, N. J., assignor to
 The M. W. Kellogg Company, Jersey City, N. J.,
 a corporation of Delaware

Application January 15, 1948, Serial No. 2,442

2 Claims. (Cl. 139—183)

1.

The present invention pertains to shuttle boxes for fly shuttle looms and more particularly to the box plates for such shuttle boxes.

The shuttle boxes located at the ends of the lay comprise front and back elongated box plates fixed to the lay and each defining a shuttle guiding surface. Each of the picker sticks moves in a slotted space at its respective end of the lay and within the shuttle box to impart motion to the shuttle. The shuttle boxes guide the shuttle as it is thrown across the lay and also act to gradually retard its motion as it enters the boxes.

One object of the present invention is to provide an improvement in box plates and especially in the construction of the front box plate to afford better checking and control of the shuttle, and straighter, smoother and steadier shuttle flight with minimum of keeling and less wear of the shuttle.

Various other objects of the present invention will be apparent from the following particular description and from an inspection of the accompanying drawings in which:

Fig. 1 is a perspective view of a front box plate pertaining to the right hand side of the loom and embodying certain features of the present invention;

Fig. 2 is a transverse section of the front box plate of Fig. 1 taken along the lines 2—2 of Fig. 1;

Fig. 3 is a transverse section of the front box plate of Fig. 1 taken along the lines 3—3 of Fig. 1;

Fig. 4 is a transverse section of the right hand shuttle box shown with the shuttle therein and embodying certain features of the present invention;

Fig. 5 is a perspective view of front box plate pertaining to the left hand side of the loom and embodying certain features of the present invention; and

Fig. 6 is a transverse section of the front box plate of Fig. 5 taken along the lines 6—6 thereof.

Referring to Figs. 1—4 of the drawing, there is shown some of the shuttle box structure on the right hand or magazine side of the loom. The shuttle box 10 on this side of the loom is secured to the lay end plate 11 by bolts as will be described and comprises a front plate 12 and a rear or back plate 13 spaced to receive the conventional shuttle 14 therebetween. The rear box plate 13 has its main body of metal and has on its inner face a shuttle guiding surface 15. Affixed to the plate 13 by means of bolts 16 is a metal ledge plate 17 which projects beyond the inner surface 15 of the box plate 13 and serves as

2.

a guide to confine the shuttle 14 in its movement into the shuttle box 10. The shuttle guide plate 17 has a lining 18 of leather or similar flexible material in a recess thereof.

5. The back box plate 13 may have the usual pivoted spring-pressed binder for protector motion control.

The front box plate 12 comprises an elongated metal body 20 desirably in the form of a casting 10 having a base flange 21, seated on the lay end plate 11, and a boss 22 near one end with an elongated opening 23 for receiving a bolt (not shown) for adjustably fastening one end of said box plate to the lay. The elongated body 20 also has a slotted lug or ear 24 near its other end for receiving another bolt (not shown) for adjustably fastening the other end of said box plate to the lay end plate 11.

The front box plate 12 has the usual elongated recess 30 serving as a thread cutter slot through which a thread cutter is adapted to operate to cut the thread from the spent bobbin prior to its ejection from the shuttle.

20. The front box plate 12 is lined with the usual shuttle guiding material 31 made for example of leather or other similar flexible cushioning material and slotted to clear the plate recess 30. The lining 31 is stretched taut and is secured to the inner face of the inner front box plate 12 by cement or suitable fastening elements such as rivets.

25. As a feature of the present invention, the front box plate 12 is constructed to effect better checking and control of the shuttle in the box, straighter, smoother and steadier shuttle flight and less wear on the shuttle. To that end, the intermediate section of the plate body 20 has a top flange 32 with a top recess 33, and seated on this flange is a metal ledge plate 34 secured to said flange by bolts 35 and extending inwardly beyond the leather lining 31 to form a guide for confining the shuttle 14 in its movement into and out of the box 10 and maintaining it against keeling during this movement. The guide plate 34 has a recess 36 receiving a suitable flexible lining material 37 such as leather secured thereto by rivets 38.

30. The flange 32 may be reinforced by a rib 40 integral with and extending between the two flanges 32 and 21 beyond the thread cutter slot 30 and has integral therewith at one end a rounded projection 41 around which a portion of the leather lining 31 is wrapped. The wrapped portion of the leather lining 31 is secured to the projection 41 by cementing or the like.

35. The recess 33 along the top plate flange 32 serves

to define a clearance between the lower face of the lining 37 and the upper edge of the lining 31 and desirably extends on its outer longitudinal side outwardly beyond the outer longitudinal edge of said lining 31. This clearance is desirable to permit easy assembly and to prevent the leather linings from gathering at the corner therebetween after a period of operation.

In the operation the guide plates 17 and 34 serve to right the shuttle 14 about its longitudinal axis in case said shuttle should be riding on one edge as it enters the shuttle box 10 and serve to guide the shuttle properly into said box and to maintain it in flat stable resting position on the lay as it moves into said box and as it is propelled from said box and across the lay during picking operations.

The guide linings 18 and 37 are at such a height that they clear the top of the shuttle 14.

Figs. 5 and 6 show the front box plate 50 on the left hand side of the loom. This front box plate is somewhat similar to the front box plate on the right or magazine side of the loom and differs mainly therefrom in the provision of a slot for the filling feeler.

The front box plate 50 comprises an elongated metal body 51 having a lining 52 of leather or similar cushioning material and provided with an elongated slot 53 for the operation of the usual filling feeler therethrough by which substantial exhaustion of filling on the bobbin is detected. Lining 52 is held in place by rivets 59. The plate body 51 has a base flange 54 and bosses 55 adapted to receive suitable bolts for attachment to the lay end plate. A top flange 56 on the plate body 51 has a recess 57 and supports a metal shuttle guide plate 58 secured to said flange by bolts 60. A recess 61 in the guide plate 58 holds a lining 62 of leather or similar cushioning material by means of rivets 63.

The back box plate (not shown) cooperating with the front box plate 50 on the left hand side of the loom is similar to the back box plate 13 on the right hand side of the loom and the two box plates on the left side with their top guide plates operate to guide and maintain the shuttle in proper position, as described in connection with the box plates on the right hand side of the loom.

While the invention has been described with particular reference to a specific embodiment, it is to be understood that it is not limited thereto but is to be construed broadly and strictly solely by the scope of the appended claims.

What is claimed is:

1. A front box plate for a loom comprising an elongated metal body having an inner upright

face and a recess on its inner upperside, a lining of cushioning material secured to said face and presented an upright shuttle guide surface extending therealong, a metal guide plate secured to the top of said metal body and projecting inwardly from said surface, said plate having a recess on its inner underside, and a lining of cushioning material in said latter recess presenting on its underside a shuttle guide surface transverse to said upright guide surface and spaced above the upper edge of said first mentioned lining as a result of said first mentioned recess.

2. A front box plate for a loom, comprising an elongated metal member having a bottom horizontal web extending the length thereof and formed with a horizontal flat bottom surface adapted to bear on the top surface of a bottom box plate, a vertical web united to said bottom web and extending the length of said elongated member, said vertical web being formed with a vertical shuttle guiding surface and being provided with an inclined thread slot having an open upper end, and a top horizontal web united to said vertical web and extending from a point proximate one end of said elongated member to the open end of said slot, said top horizontal web having a stepped top surface comprising two vertically spaced horizontal surfaces, the lower of said spaced surfaces intersecting said vertical guiding surface, a metal guide plate on the upper of said spaced surfaces secured to said top horizontal web and extending substantially the length of said top horizontal web, said guide plate extending inwardly from said vertical guiding surface and having a recess in its extending under side, a lining of cushioning material in said recess, a lining of cushioning material covering said vertical shuttle guiding surfaces and terminating at the top edge thereof whereby the shuttle contact surfaces defined by said cushioning material are separated by a distance substantially equal to the vertical distance between said vertically spaced horizontal surfaces.
